UNITED STATES PATENT OFFICE.

SAMUEL E. RAHE, OF NEW YORK, N. Y.

MATCH-MACHINE.

1,184,994.

Specification of Letters Patent. Patented May 30, 1916.

Application filed November 29, 1915. Serial No. 63,922.

To all whom it may concern:

Be it known that I, SAMUEL E. RAHE, a citizen of the United States, and a resident of the city of New York, borough of Brooklyn, county of Kings, and State of New York, have invented a new and useful Improvement in Match-Machines, of which the following is a full, clear, and exact description.

10 My invention relates to improvements in match machines such as take match splints from a hopper and insert them in a carrier preparatory to dipping them in the several compositions.

15 My invention relates more particularly to the sticking head and accessory parts, and the object of my invention is to produce a simple and reliable device which will keep clean the splint carrying channels of the 20 sticking head, and also serve to assist in guiding the splints to the carrier.

25 My invention is also intended to provide means for the purpose above described which can be attached to existing types of machines without difficulty, and further to produce a device of the character stated which is simple, inexpensive, and positive in action.

30 Reference is to be had to the accompanying drawings forming a part of this specification, in which similar reference characters indicate corresponding parts in all the views.

35 Figure 1 is a broken plan view of a portion of a match station or splint inserting part of the machine. Fig. 2 is a broken front elevation of the mechanism shown in Fig. 1. Fig. 3 is a cross section on the line 3—3 of Fig. 2 with one of the partitions 14 removed, and showing the sticking head withdrawn from a carrier. Fig. 4 is a view 40 similar to Fig. 3 but with the sticking head moved inward so as to insert the splints in the carrier, and Fig. 5 is a broken inner end 45 elevation of a part of the sticking head and the partitions or guide plates.

50 The machine is provided with a housing 10 which is really a lower extension of the ordinary splint containing hopper, and for 55 convenience has flanges 11 at the top on which runs the shaker 12 having cross blades 13. The hopper is generally arranged upon the member 12, and the blades 13 moving back and forth with the member 12 serve to straighten the match sticks and drop them into the sticking mechanism below.

The above mechanism is not shown or described in detail because it forms no part of this invention. The housing 10 is provided with numerous guide partitions 14 which are of thin metal and are in parallel relation, these projecting rearward from the housing to a point near the carrier 15. The plates or partitions 14 are chiefly intended as cleaning plates, though they also serve as 60 guide plates, and they are spaced apart a little more than the thickness of the match splints so that the splints as they fall must lie straight between them. The carrier 15 can be of any usual or preferred type capable 65 of receiving match splints presented endwise to it, and as shown it is a common construction comprising a plate 15 having holes 16 in which the ends of the match splints 22 are inserted.

70 A sticking head 17 reciprocates immediately below the housing 10, and this is provided with channels 18 and 19 at different levels, in which the match sticks 22 lie, and at the outer end of the channels or 80 grooves are shoulders 20 and 21 against which the outer ends of the match splints rest so that as the sticking head moves inward to a point near the carrier 15, the splints will be carried to the carrier and 85 their ends inserted in the holes 16 thereof, or in equivalent holding devices if another form of carrier is used. The sticking head 17 is longitudinally slotted as shown at 23 at points between the several channels 18 90 and 19 as shown best in Fig. 5, and the guide plates or cleaning plates 14 which are secured to the housing 10, fit into these slots, so that when the sticking head is reciprocated the members 14 act to clean out the 95 channels as they will strike any slivers or obstructions which may be lodged therein and push them from the sticking head as the latter is retracted from its advanced position. I have shown the sticking head 17 100 provided with a shank or extension 17^a by means of which it can be reciprocated, but this has nothing to do with the invention, which lies wholly in the arrangement of the guide plates or partitions 14 and their 105 relation to the housing or hopper extension and the sticking head.

110 It will be clearly seen that the particular means of holding the splints on the sticking head, can be departed from, and that the form of carrier can be changed without affecting the principle of the invention.

In practice the match splints are dropped down between the plates 13 and the guide or cleaning plates 14, into the channels of the sticking head. When the latter is moved inward against the carrier, rows of splints 22 are carried inward and stuck in the carrier, and on its return movement the sticking head will pick up a new series of splints, the carrier meanwhile being stepped forward in the customary manner so as to bring a new set of holes into alinement with the splints in the sticking head.

I claim:

1. In combination, a reciprocating sticking head having means for holding match splints thereon and slots between the splint holding devices, of cleaning plates supported above the sticking head and entering the aforesaid slots, and means for feeding match splints between the said plates to the sticking head.
2. In a match machine the reciprocating sticking head having splint holding means

thereon, a housing above the sticking head forming a hopper extension, and cleaning and guide partitions supported in the housing and projecting rearwardly therefrom, said partitions being arranged between the splint holding means of the sticking head.

3. In a match machine, the combination with a carrier and a reciprocating sticking head perpendicular to the carrier, said sticking head having splint holding grooves or channels therein, of a housing forming a hopper extension arranged above the sticking head, said housing being spaced apart from the carrier, and parallel partitions arranged within the housing and projecting to a point near the carrier, said partitions being also arranged between the splint holding channels of the sticking head.

SAMUEL E. RAHE.
